UNITED STATES PATENT OFFICE

FRANK L. OHLER AND ROLAND P. FRENCH, OF TOLEDO, OHIO, ASSIGNEES TO THE HAUGHTON ELEVATOR & MACHINE COMPANY, OF TOLEDO, OHIO, A CORPORATION OF OHIO

ELEVATOR SAFETY DEVICE

Application filed December 16, 1929. Serial No. 414,342.

This invention relates to an elevator safety device adapted to be tripped into operation to stop the car abruptly when its speed exceeds a predetermined limit. In cars which normally travel at a comparatively low speed, in order to reduce the cost of installation as far as is practicable consistent with safety, it is common to provide a safety device known as a "roll grip," in which a roller is wedged 10 between an abutment carried by the car and the guide along which the car travels.

In the operation of roller grips, as heretofore constructed, the tremendous pressure developed by the momentum of the car frequently causes the roller to mutilate the surfaces which it engages, especially the edges thereof, and often causes the roller to become partially embedded so that it is extremely difficult to withdraw it.

With the above conditions in mind, it is the object of the present invention to provide a device of the character stated which is simple, practical and comparatively inexpensive, which may be operated with comparatively little damage to the parts engaged, and which may be easily restored to normal or inactive position.

The construction of the invention, in its present embodiment, and the advantages thereof, will be more particularly explained in connection with the accompanying drawings, in which

Figure 1 is a more or less diagrammatic view illustrating the adaptation of the invention to an elevator installation.

Figure 2 is a horizontal section through the bottom of a car with the invention installed thereon.

Figure 3 is a front elevation of the parts shown in Figure 2.

Figure 4 is a side elevation of the invention showing the same in normal or inactive position.

Figure 5 is a view similar to Figure 4, but showing the position of the parts after the device has been tripped to stop the car.

As illustrated in the drawings, the invention is associated with an elevator car 1 which is connected to a counterweight 2 by ropes 50, or cables 3. These ropes or cables pass over

a drum 4, which may be driven in any suitable manner to move the car vertically between guide rails 5 while the counterweight 2 moves along the guide rails 6. An endless governor rope 7 is connected normally, for travel with the car 1 and passes about an upper sheave 10 and about a lower tensioning sheave 9. This governor rope has a ball 11 secured thereto and normally held in a clamp 12 which is attached to the top of the car. The clamp 12 is held in gripping relation to the ball 11 by a spring 13, which will yield to permit the ball to escape only when the rope 7 is suddenly stopped while the car continues to travel downwardly. In order that such operation may take place when the downward travel of the car exceeds a predetermined speed, a fly-ball governor 14 is mounted in the pent house and geared to a shaft 15 on which the sheave 10 is mounted. This governor is so arranged that when it reaches a predetermined speed, it actuates an eccentric 16 to cause the latter to clamp the rope 7 and stop its movement. The rope 7 has a branch 8 which is secured by a clamp 17 to a tripping lever 18 which trips the safety device as the car continues its travel.

As shown in Figures 2, 3, 4 and 5, the tripping lever 18 is carried by an arm 19 which is secured to a shaft 20. The shaft 20 is mounted for rocking movement in brackets 21 which are secured to bars 22 on the bottom of the car. These brackets 21, one of which is located at each side of the car, are formed with shoes or channel portions which receive the guide rails 5, each channel portion being formed with a vertical face 23 contiguous to the face of the guide rail and with an opposed face 24 which is inclined upwardly toward the opposite face of the rail 5. An arm 25, which is secured to the shaft 20, carries at its end a roller 26, which is adapted to move upwardly between the guide rail 5 and the inclined face 24 whenever the tripping device is actuated to rock the shaft 20. A spring 27 is connected to the shaft 20 and normally holds the arm 25 and roller 26 in inactive position with the position of the roller limited by a pin 28 against which it rests. It will be understood that when the device 100

is tripped to rock the shaft 20, the roller 26 at each side of the car will be wedged between the rail 5 and the inclined face 24 to stop the downward movement of the car, the mounting of the roller allowing for the arcuate movement of the end of arm 25. In order to prevent damage as far as possible and to prevent the roller 26 from becoming stuck so hard as to cause difficulty in removing it, a 10 gib 29, preferably of case hardened steel, rests against the face 24. This gib has a laterally turned end 30 which is mounted on a stud 31 and yieldably held against a shoulder 32 on the bracket by a spring 33. By providing these removable gibs it is practicable to make them sufficiently hard so that they will not be easily crushed by the momentum of the car, and if they are damaged they may be very easily replaced. The yieldable character of the mounting for these gibs, in connection with their inclination, makes it easy to withdraw the rollers 26 along with the gibs, after the safety stop has been effected.

A shoe 34 is secured to each bracket 21 by means of an angle 35 and may be adjusted by means of a screw 36 to secure the proper working clearance between the shoe and the guide rail 5. The roller arms 25 are so set on the shaft 20 as to bring the 25 rollers 26 closely against the bottoms of the channel portions of the brackets 21 and at an appreciable distance from the free edges of the channel, so that when the safety device is actuated, the outer edges of the channels 30 will not be crushed. The bottoms of these channels against which the rollers bear, are raised somewhat, leaving deeper narrow channel portions 37 for receiving the inner edges of the rails 5. Thus the inner edges 35 of the rails 5 are always completely protected against crushing.

While the invention is primarily intended for installations where the travel of the car does not exceed 100 feet per minute, it is not necessarily limited to such use. Many of the details of the construction may also be modified without departing from the scope of the invention as claimed.

What we claim is:

- 50 1. The combination with a vertical guide rail, of a body movable adjacent said rail, a clamping member carried by the body and having converging faces, one of said faces being engageable with the rail, a gib 55 on the other face, a roller movable into wedging engagement between the gib and the rail, and means for holding said gib, said holding means being yieldable with the gib in the direction of divergence of said faces to facilitate the release of the roller.
- 60 2. The combination with a vertical guide rail, of a body movable adjacent said rail, a clamping member carried by the body and having converging faces, one of said 65 faces being engageable with the rail, a gib

on the other face, a roller between the rail and the gib, an arm on which the roller is carried, said arm being mounted on said body and movable thereon to bring the roller into wedging engagement between the gib and the rail, and means for holding said gib, said holding means being yieldable with the gib in the direction of divergence of said faces to facilitate the release of the roller.

3. The combination with a vertical guide rail, of a body movable adjacent said rail, a clamping member carried by the body and having converging faces, one of said faces being engageable with the rail, a gib on the other face, a roller between the rail and the gib, an arm on which the roller is carried, a rock shaft mounted on said body and having said arm secured thereto, a lever secured to said shaft and operable to rock the same to bring the roller into wedging engagement between the gib and the rail, and means for holding said gib, said holding means being yieldable with the gib in the direction of divergence of said faces to facilitate the release of the roller.

4. The combination with a vertical guide rail, of a body movable adjacent said rail, a member carried by the body and formed with a channel portion embracing said rail, one side of the channel having a vertical face contiguous to the rail, the other side of the channel having a face spaced from the rail and upwardly convergent, a wedge member movable into wedging engagement between the rail and said convergent face, and means for maintaining said wedge member at an appreciable distance from the free edge of said channel portion and the edge of said rail to prevent crushing of said edges.

5. The combination with a vertical guide rail, of a body movable adjacent said rail, a member carried by the body and formed with a channel portion embracing said rail, one side of the channel having a vertical face contiguous to the rail, the other side of the channel having a face spaced from the rail and upwardly convergent, and a wedge member movable into wedging engagement between the rail and said convergent face, the bottom of said channel having a portion adjacent said vertical face which is deeper than the rest of the bottom, to receive the edge of said rail and protect it from the crushing effect of the wedge member.

6. The combination with a vertical guide rail, of a body movable adjacent said rail, a member carried by the body and formed with a channel portion embracing said rail, one side of the channel having a vertical face contiguous to the rail, the other side of the channel having a face spaced from the rail and upwardly convergent, a gib on said convergent face, a wedge member movable into wedging engagement between the gib and the rail, means for maintaining said

wedge member at an appreciable distance from the free edge of said channel portion and the edge of said rail to prevent crushing of said edges, and means for holding said gib, said holding means being yieldable with the gib in the direction of divergence of said faces to facilitate the release of the wedge member.

7. The combination with a vertical guide rail, of a body movable adjacent said rail, 10 a member carried by the body and formed with a channel portion embracing said rail, one side of the channel having a vertical face contiguous to the rail, the other side of the channel having a face spaced from the rail and upwardly convergent, a gib on said convergent face, a wedge member movable into wedging engagement between the gib and the rail, the bottom of said channel having a portion adjacent said vertical face 15 which is deeper than the rest of the bottom to receive the edge of said rail and protect it from the crushing effect of the wedge member, and means for holding said gib, 20 said holding means being yieldable with the gib in the direction of divergence of said faces to facilitate the release of the wedge member.

In testimony whereof we have hereunto signed our names to this specification.

FRANK L. OHLER.
ROLAND P. FRENCH.
